UNITED STATES PATENT OFFICE.

HUBERT KING, OF PHILADELPHIA, PENNSYLVANIA.

DESIGN FOR A MOP OR BROOM HOLDER.

SPECIFICATION forming part of Design No. 28,233, dated February 1, 1898.

Application filed December 21, 1897. Serial No. 662,942. Term of patent 14 years.

To all whom it may concern:

Be it known that I, HUBERT KING, a citizen of the United States, residing at Philadelphia, (Germantown,) in the county of Philadelphia and State of Pennsylvania, have invented and produced a new and original Design for a Suspending Mop or Broom Holder, of which the following is a specification, reference being had to the accompanying drawing, forming part hereof, illustrating in perspective a suspending mop or broom holder embodying the characteristic features of design as to shape or configuration of my said invention.

The leading feature of my design consists of the shape or configuration of the suspending mop or broom holder.

Referring to the drawing, A represents the holder, provided with side latticed frames a and a' and end open pieces a^2 and a^3 . The side latticed frames a and a' at one of their ends are provided with perforated ears a^4 and a^5 . In the front end piece a^3 are formed curved vertical strips a^6 and a^7 and a tapering lug a^8 in the base portion of the same about the middle thereof.

b is a spanning or bracing cross-strip en-

gaging the side frames and provided with claw-feet b' , which bear against and also embrace the latticed side frames, as illustrated. At the base of each of the side frames and 30 projecting therefrom is a series of rings c of irregular contour or outline.

d are lugs projecting from the middle strips of the respective latticed side frames of the holder and having a base d^2 .

e are movable bars having heads or knobs e' at the free ends thereof and lugs e^2 intermediate of their ends and extending upward from the surface of said bars.

Having thus described my invention, what 40 I claim as new, and desire to secure by Letters Patent, is—

The design for a suspending mop or broom holder, substantially as shown and described.

In testimony whereof I have hereunto set 45 my signature in the presence of two subscribing witnesses.

HUBERT KING.
